UNITED STATES PATENT OFFICE.

GEORGE LAUTERER, OF CHICAGO, ILLINOIS.

PERAMBULATOR.

No. 839,009.

Specification of Letters Patent.

Patented Dec. 18, 1906.

Application filed February 23, 1906. Serial No. 302,574.

To all whom it may concern:

Be it known that I, GEORGE LAUTERER, a citizen of the United States, residing at Chicago, in the county of Cook and State of Illinois, have invented a new and useful Perambulator, of which the following is a specification.

My invention relates to improvements in perambulators used in initiatory exercises in which the candidate is caused to experience the sensations as of diverse and sundry movements of the body and arms; and the objects of my invention are to provide a bed which oscillates in a number of directions in conjunction with a running-gear provided with an axle-crank and elliptical or circular wheels adapted to produce in the candidate the sensation of gyrating and flying as a bird. I attain these objects by the mechanism illustrated in the accompanying drawings, in which—

Figure 1 is a perspective of the perambulator, showing the candidate in position on the bed. Fig. 2 is a modification showing elliptical wheels. Fig. 3 shows a second modified form of fulcrum for the bed in combination with a spiral spring. Fig. 4 shows a third modification substituting the bumpers *q q* for the spring *p*. Fig. 5 shows a fourth modification of such fulcrum, consisting of a universal joint in connection with supporting-springs.

In detail, *a* is the frame, which rests, by means of suitable journals, upon the axle *b* and is provided with the swivel-wheel *c*. Upon the frame *a* is a stand *d*, formed of the uprights *e e* and the braces *f f*, and is rigidly secured to the frame *a*. *g* is a rod extending through the apex of the stand *d* and forms the shaft upon which the bed *h* oscillates. At the forward end the bed *h* is provided with a pitman *i*, which connects with the crank *j*, formed integrally with the axle *b*. The wheels *k k* are rigidly fixed to the axle *b*, so that the movement of the perambulator causes a vertically-oscillating seesaw motion of the bed *h*. At each side of the bed *h* is hinged an arm *l*, which at the outer end is loosely supported on the frame *a* by means of the rod *m*, so that the movement of the bed *h* causes a contra movement of the arms *l l*.

In the modification Fig. 2 the wheels of the running-gear, as shown in Fig. 1, are in the elliptical form *k' k'*, so as to afford sundry

motions in conjunction with the movement of the bed *h* and arms *l l*, dependent on the radial position of the wheels on the axle relative to each other—*i. e.*, if the ellipses are on the corresponding center their revolution will cause a leaping or flitting motion, and if on the opposing center a regular side-to-side motion will be produced. It is obvious that any variety of relative intermediate motion may thus be provided.

In the modification Fig. 3 the stand *d* consists of the upright *e'*, which at the apex *e'* is rigidly secured to the bed *h* and is movably pivoted upon the rod *n* and stirrup *o*. The spring *p* passes over the rod *n* and is fixed at one end to the stirrup *o* and at the opposite end to the rod *n*, thus permitting an oscillating seesaw movement of the bed *h*, as well as a longitudinal movement, in so far as the backward and forward thrust of the bed *h* shall be dependent upon the size and tensile strength of the spring in conjunction with the pushing and pulling force of the pitman and crank-axle. The spring is adapted to prevent the bed from falling too far backward or forward.

In the modification Fig. 4 the parts are as described in the modification, Fig. 3, except that for the spring *p* are substituted the bumpers *q q* to permit only a reasonable thrust of the upright *e'*.

The modification Fig. 5 shows the stand *e'* rigidly secured to the frame *a* and provided with a ball at its apex adapted to receive the socket part which is fixed to the bed *h*, thus permitting the bed to oscillate in any direction subject to the restraint of the springs *r r*. I thus provide a primary motion to the bed *h*, a differential movement to the arms *l l*, and any number of subsidiary movements by means of the elliptical wheels.

What I claim is—

1. In perambulators, the combination with the running-gear, of a bed permanently pivoted upon said gear and provided with arms, and means for relatively oscillating said bed and arms substantially as described.

2. In perambulators, the combination with the running-gear, of a bed permanently attached to said gear, arms movably attached to said bed, means for oscillating said gear, means for oscillating said bed and means for oscillating said arms, substantially as described.

3. In perambulators, the combination with the running-gear of a bed permanently pivoted upon said gear, arms movably attached to said bed, means for imparting a number of movements to said bed, means for imparting a movement to said arms relative to said bed and gear and means for im-

parting a number of subsidiary movements to all said parts as a whole, substantially as described.

GEORGE LAUTERER.
